UNITED STATES PATENT OFFICE

2,192,090

KNITTED FABRIC

Harry McAdams, Reading, Pa., assignor to Nolde and Horst Company, Reading, Pa., a corporation of Pennsylvania

Original application June 14, 1934, Serial No. 730,666. Divided and this application May 23, 1935, Serial No. 23,085.

2 Claims. (Cl. 66—201)

This invention relates to improvements in knitted fabric, and has particular reference to a seamless knitted fabric such as set forth in my copending application, Serial No. 730,666, filed 5 June 14, 1934, the present application being a division therefrom.

The primary object of this invention is the provision of a seamless tubular fabric which may be knitted upon a double feed type of rotary cylinder knitting machine, and wherein may be incorporated horizontal striped effects, selective reverse plating, and selective "color within color" striped or spotted patterning in correlation to the horizontal striping and reverse plating patterned effects.

A further object of this invention is the provision of an improved tubular knitted seamless fabric which may embody selective reverse plating, horizontal striping, and patterned striping 20 and designing upon a machine such as set forth in my co-pending applications, Serial Nos. 730,666 and 662,354.

Other objects and advantages of this invention will be apparent during the course of the following detailed description.

25 In the accompanying drawings, forming a part of this specification, and wherein similar reference characters designate corresponding parts throughout the several views,

Figure 1 is a side elevation of a stocking, showing in fragmentary detail the plating and selective pattern wrapping which may be provided in the stocking in accordance with my present invention, and as set forth in my parent application, Serial No. 730,666, of which the present application is a division.

Figure 2 is a fragmentary inside view of a section of the stocking shown in Figure 1 on an enlarged scale, and showing more particularly the plating and wrapping yarns, and the float 40 portions of the latter.

Figure 3 is an enlarged section of the fabric of Figures 1 and 2, showing the face thereof and the stitches of the various yarns forming the body, plating, reverse plating, and complementary 45 selective needle wrapped patterning yarns.

In the drawings, wherein for the purpose of illustration is shown only one of a large variety of patterns which may be embodied in seamless tubular knitted fabrics, according to my present 50 invention, the letter P may generally designate such fabric.

Generally the machine upon which the improved patterned fabric may be knitted comprises a double feed of both body and plating yarns so as to produce two knitted courses of the fabric for each revolution of the cylinder. In addition, horizontal striped effects may be produced by changing the body and plating yarns in accordance with the teaching set forth in my co-pending

application, Serial No. 662,354. The machine also embodies wrapping yarn feeds for each main yarn feed of the machine, and these wrapping yarn feeds may each be capable of producing in the knitted fabric a "color within color" striping or design spotting effect. The plating and wrapping feeds are of course selective so far as needle and course regulation are concerned.

Referring to the fabric P, as shown in the drawings, the same represents a seamless knitted stocking although the features of the invention are not to be construed as limited solely to a stocking. In general the design includes reversely plated diamond shaped areas 500, the stitches of which are stepped from course to 15 course to provide diamonds extending forty wales in width and eighty courses in length. Of course the reversely plated patterns may vary as to shape and size.

Inasmuch as by reference to my parent application, Serial No. 730,666, it will be seen that the fabric is knitted upon a double feed type of machine, separate pairs of knitting yarns are used in the plated areas for adjacent courses. Thus, knitting yarns 81 and 83, which may be appropriately designated as gray and black yarns 25 respectively, are used to knit stitches in the fabric in one course, and in the adjacent course gray and black yarns 93 and 94 respectively knit stitches therein. Of course the two courses wherein the plating is effected from the yarns 30 81—83 and 93—94 are produced during the same revolution of the cylinder of the knitting machine upon which the seamless fabric is produced. The reverse plating in the patterned area will be identical for the pairs of courses thus knitted 35 during any single revolution of the cylinder, as will be seen by reference to Figure 3 of the drawings.

As will be seen from Figure 3 of the drawings that the reverse plated pattern is stepped one 40 wale at each two courses. Knitting proceeds in the reverse plated pattern starting at the top of the diamond at 502, as shown in Figure 1 and proceeds according to the pattern lug lay-out on 45 the patterning drum of the machine, as set forth in my above identified co-pending parent application, of which the present application is a division.

It will of course be understood that many varied 50 reverse plated designs may be provided upon the fabric knitted upon the machine of my parent application.

Referring to the needle wrapping yarns and their control so far as the seamless fabric is concerned, with respect to the plated areas, the 55 needle wrapping yarns are controlled upon the machine as set forth in my co-pending application. They may be typically identified in the present example as red and yellow yarns. The 60

yellow yarns are diagonally knitted to provide wrap stripe diamonds, the diagonal stripes of these yellow yarns crossing each other to provide the small wrap stripe diamonds in a cooperative patterned effect with respect to the reversely plated diamonds. The red yarns are spotted in the centers of the diamonds produced by the yellow diagonal striping yarns. This produces the so-called "color within color" effect of needle wrapped yarns.

The striping is produced upon needles which are selectively controlled in cooperative relation with a control feed of the striping yarns thereto. In the double feed machine upon which the fabric is produced there is a double feed of needle wrapped yarns and at each wrap yarn feed the threads may be regulated in the manner set forth in my co-pending applications Serial Nos. 662,354 and 591,689.

The red spotting yarns are fed to a selected arrangement of needles. Thus the spotting yarns indicated at 600^a in Figure 2 of the drawings may produce knitted stitches 600 in the fabric. By means of pattern manipulation of the feed fingers and needles, as has been set forth in my co-pending applications above referred to, other red spotted areas 601 may be provided in other striped diamond areas at different courses than those courses in which the stitches 600 appear, as is clearly indicated in the drawings. Inasmuch as two courses of the fabric are knitted for each revolution of the cylinder in the double feed type of machine whereon the fabric is knitted, such as set forth in my said co-pending application, Serial No. 730,666, it will be understood that the red striping yarns fed to the needles as directed by yarn fingers and cams at one feed of the machine will appear only in alternate courses, as is clearly designated in Figure 3. Since at each feed of the machine the yellow striping yarns are directed to the elevated and selected needles they appear in adjacent courses of the fabric to complete the bordering or other desired wrap stripe pattern design. This enables each yellow striping or patterning yarns to appear in each course of the fabric.

One of the striping yarns may be fed to a selected arrangement of needles to produce the stitches 628 shown in the fabric in Figure 3 of the drawings, and another of the yellow patterning yarns may be fed by its patterning means to other selected arrangements of needles in order to produce patterning stitches 640, as shown in Figure 3 of the drawings. These stitches 628 and 640 are of course in complementary relation to complete the diamond-shaped pattern design, and the portions of these respective yellow yarns may be floated both walewise and coursewise at the inside of the fabric, wherever desired. By this arrangement in utilizing several different lap or needle wrapped yarns for each design, more complicated pattern designs may be provided than was previously possible, and it is not so necessary to float the wrapping yarns coursewise across the width of the design; thus eliminating many float threads which would ordinarily occur in wrap pattern designs, where the wrapping yarns are floated between widely spaced stitches in the same or adjacent courses. It should thus be noted that in the seamless tubular fabric each yellow patterning or wrap stripe yarn may be produced in adjacent courses of the fabric and

floated at the inside of the fabric wherever desired notwithstanding that I knit the fabric upon a double feed machine. However, these adjacent courses of the web of the fabric are formed of different plating or body yarns.

The inside of the fabric P shown in Figure 2 has shown thereon the float portions 600^a of the red patterning yarns, and the small float portions of the yellow striping yarns from course to course, etc.

It will of course be realized that many different reverse plated patterns and striping and patterned effects of the needle wrapping yarns may be produced in the fabric, as may be desired.

From the foregoing it will be seen that a seam-
less tubular fabric has been provided wherein the
body web of the article is formed of a plurality
of plating yarns controlled so as to provide plated
design areas, such as by reverse plating; the
plating yarns in non-adjacent courses being the
same and the remaining courses being formed
of other plating yarns. In this relation a selected
arrangement of striping yarns are wrap striped
with the stitches produced by the plating yarns,
and if desired each of these wrapping yarns are
knitted into adjacent courses. In addition to
that a "color within color" wrap stripe or needle
wrapped stitch effect is produced with the afore-
mentioned needle wrapping yarns and other
needle wrapping yarns.

Various changes in the formation of the seam-
less tubular fabric, as to character, method of
knitting the same, and design patterning and
plating may be made not only to the article, but
also to the method, without departing from the
spirit of the invention or the scope of the claims.

I claim:

1. A knitted fabric including a tubular seam-
less body of interlinked courses having relatively
spaced courses thereof formed out of a plurality
of body yarns knitted in both normal and reverse
plated relation, the remaining courses of the fab-
ric being formed of a plurality of other body
yarns also knitted in normal and reverse plated
relation and in complementary pattern provid-
ing relation with the normal and reverse plated
portions produced of the first mentioned pair of
body yarns, and a plurality of wrap yarns inter-
knitted with predetermined stitch loops in suc-
cessive courses of the fabric in complementary
patterned relation with the normal and reverse
plated areas of the fabric.

2. A knitted fabric including a tubular seam-
less body of interknitted courses having rela-
tively spaced courses thereof formed out of a
plurality of body yarns knitted in both normal
and reverse plated relation, the remaining courses
of the fabric being formed of a plurality of
other body yarns also knitted in normal and re-
verse plated relation and complementary to the
normal and reverse plated portions knitted out
of the first mentioned pair of body yarns, a con-
trastingly colored wrap yarn continuously inter-
knitted with said body yarns in a patterned re-
lation in successive courses of the fabric and a
second wrap yarn also interknitted with the body
yarns in different stitches thereof than the first
wrap yarn in at least some of the same courses
wherein the first wrap yarn is knitted and in a
complementary patterned relation therewith.

HARRY MCADAMS.
